United States Patent Office

Des. 181,598

Patented Dec. 3, 1957

181,598

CIRCLE SHEAR

Frederick E. Munschauer, Jr., Buffalo, and Robert George Beiter, Elma, N. Y., assignors to Niagara Machine & Tool Works, Buffalo, N. Y.

Application September 19, 1956, Serial No. 43,002

Term of patent 14 years

(Cl. D55—1)

Fig. 1.

Fig. 2.

Fig. 1 is a perspective view of a circle shear showing one end and one side thereof, showing my new design; and

Fig. 2 is a similar perspective view of the circle shear of Fig. 1 but taken from an opposite direction and showing the opposite end and opposite side thereof.

We claim:

The ornamental design for a circle shear, as shown.
